UNITED STATES PATENT OFFICE.

OTUS PICKELSMER, OF GREENVILLE, SOUTH CAROLINA.

IRONER AND MOLDER FOR OVERALLS AND TROUSERS.

1,354,438.

Specification of Letters Patent. Patented Sept. 28, 1920.

Application filed March 19, 1920. Serial No. 367,275.

To all whom it may concern:

Be it known that I, OTUS PICKELSMER, a citizen of the United States, residing at Greenville, in the county of Greenville and 5 State of South Carolina, have invented certain new and useful Improvements in Ironers and Molders for Overalls and Trousers; and I do hereby declare the following to be a full, clear, and exact description of the invention, such as will enable others skilled in 10 the art to which it appertains to make and use the same.

The present invention relates to improvements in appliances for use in laundries and 15 cleaning establishments, and more particularly refers to an improved ironer and molder for overalls, trousers, and the like.

It is an object of the present invention to provide an improved appliance of this character that will impart a definite crease to the 20 garments in a more convenient and expeditious manner than has heretofore been possible with the other forms of similar appliances.

25 Another object of the present invention resides in providing an appliance of simple and inexpensive construction, which admits of adjustability to fit garments of varying sizes and shapes, and which will impart a more definite crease than it has been heretofore possible to successfully obtain.

In the accompanying drawings forming a part of this application, and in which similar reference symbols indicate corresponding parts in the several views:

Figure 1 is a view in elevation of an improved laundry appliance as constructed in accordance with the present invention.

Fig. 2 is a vertical central sectional view 40 taken through the device.

Fig. 3 is a horizontal section taken on the line 3—3 in Fig. 1.

Fig. 4 is a similar view taken on the line 4—4 in Fig. 1.

45 Fig. 5 is a fragmentary enlarged vertical sectional view showing the tip of the appliance; and

Fig. 6 is a fragmentary sectional view showing the adjustment detail.

50 Referring more particularly to the drawings, 1 designates a stand upon which is placed a casting 2 being substantially in the form of one of the legs of the overalls or trousers, and which may be made to conform 55 in shape approximately to the sleeve of a garment.

The casting is closed at its upper end, which is narrower than the enlarged lower end, at the base of which is a flange 3 resting upon a base plate 4. Asbestos, or other 60 suitable packing 5, may be placed between the flange 3 and the plate 4, and suitable fastenings 6, such for instance as the bolts shown, may be passed through these various parts and through the stand 1 to hold the 65 casting 2 securely thereon.

The casting is made substantially flat in one direction, or corresponding to an oval in cross section as illustrated in Figs. 3 and 4, and the longitudinal edges 7 and 8 thereof 70 are curved inwardly as indicated in Fig. 1.

As shown most clearly in Fig. 5, the tip of the casting is provided with a groove 9 through which passes a spring tension wire 10 preferably of brass. This wire 10 passes 75 down on opposite sides of the inwardly curved edges 7 and 8 of the casting 2, and has its lower ends threaded as indicated at 11 in Fig. 6. These threaded ends 11 pass through the flange 3, asbestos packing 5, the 80 base plate 4, and the stand 1. Winged nuts 12 are screwed on the threaded ends 11 and take against the under side of the upper portion of the stand 1. The nuts 12 admit of adjusting the tension of the wire 10. 85

Within the casting 2 is formed a vertical partition 13, the upper end of which is spaced from the top of the inside portion of the casting in order to allow the steam or other heat medium to pass from one compartment 90 to the other within the casting. An inlet pipe 14 is shown connecting through the base with one compartment of the casting 2, while an exit pipe 15 communicates at the base portion with the compartment to the 95 opposite side of the partition 13.

In the use of the device the leg or sleeve of a garment is slipped over the casting 2, which may be placed vertically as shown in the drawings or horizontally if preferred, 100 and steam is then admitted through the pipe 14 to the base of the casting at one side of the partition 13. The steam is caused to rise in the casting 2 and to pass about the upper end of the partition, thence down the 105 other side of said partition and make its escape through the exit pipe 15. The steam will thus impart heat to the casting 2, and when the garment is drawn tightly thereover the effect will be to press the same, removing 110 the wrinkles and restoring the smooth condition of the cloth.

Preferably the winged nuts 12 are loosened so as to allow the wire to become slack before the garment is placed over the casting 2, and the winged nuts 12 may be thereafter tightened in order to draw the wire 10 taut within the garment, which will thereupon impart a seam or crease to the same. The use of the winged nuts 12 allows the desired crease to be given as a wide adjustment is imparted.

It is obvious that those skilled in the art may vary the details of construction and arrangements of parts without departing from the spirit of my invention, and therefore I do not wish to be limited to such features except as may be required by the claims.

I claim:

1. A device of the character described including a stand, a hollow tapering casting being closed at its upper end and having a lower open end supported upon said stand, said casting having a partition therein separating the interior thereof into two compartments communicating only at the upper end thereof, means for introducing a heat-carrying medium into the lower end of one of the compartments, means for conveying off the medium after the same has circulated through both of the compartments

from the lower end of the other compartment, and a tension wire associated with said casting and being adjustable to form creases in the garments, substantially as described.

2. A device of the character described including a stand, a tapering casting substantially oval in cross section having its upper end closed and its lower wider end open and provided with a flange, a base plate on the stand on which the flange rests, a packing placed between said flange and base plate, a partition in the casting dividing the same into two adjacent and longitudinally extending compartments communicating only at their upper ends, means for introducing steam to the lower end of one of the compartments and for conveying the same off at the base of the other compartment, said casting having a groove at its upper end extending in the direction of the longitudinal axis thereof, a spring tension wire fitted in said groove and extending downwardly adjacent to the curved edges of said casting, the lower ends of said wire being threaded and passing through the stand, and nuts running on said threaded portions beneath the stand for tensioning said wire, substantially as described.

OTUS PICKELSIMER.
